BY

Richard Lier ATTORNEY.

UNITED STATES PATENT OFFICE.

WILLIAM LEUCKERT, OF ASTORIA, NEW YORK.

DESIGN FOR AN AUTOMOBILE PARKING-LIGHT.

59,239.

Specification for Design.

Patented Oct. 4, 1921.

Application filed March 21, 1921. Serial No. 454,296. Term of patent 7 years.

To all whom it may concern:

Be it known that I, WILLIAM LEUCKERT, a citizen of the United States, residing at Astoria, in the county of Queens, State of New York, have invented a new, original, and ornamental Design for Automobile Parking-Lights, of which the following is a specification, reference being had to the accompanying drawing, forming part thereof.

Figure 1 is a side elevational view of an automobile parking light showing my new design, and

Fig. 2 is a plan view thereof.

I claim:

The ornamental design for an automobile parking light as shown.

WILLIAM LEUCKERT.
